UNITED STATES PATENT OFFICE.

BARTHOLOMEW CONNOLLY, OF TONOPAH, NEVADA.

FLYING-MACHINE.

No. 852,221.

Specification of Letters Patent.

Patented April 30, 1907.

Application filed April 13, 1906. Serial No. 311,449.

To all whom it may concern:

Be it known that I, BARTHOLOMEW CONNOLLY, a citizen of the United States, residing at Tonopah, in the county of Nye and State of Nevada, have invented new and useful Improvements in Flying-Machines, of which the following is a specification.

My invention relates to an aerial apparatus; and it consists in the combination of mechanism and devices whereby power is transmitted, with the object of raising and propelling the apparatus.

In the accompanying drawings, Figure 1 is a perspective view of my improved apparatus. Figs. 2 and 3 are details of construction.

My invention comprises a sufficiently strong frame A made of any suitable or desired shape, and preferably of aluminium or like material. Upon this frame is carried an engine or motor 2, from which power is derived and transmitted to propel the apparatus. It will be understood that any suitable motor may be applied. I have found that gasoline or an equivalent internal combustion engine is very suitable for the purpose. From this engine power is transmitted by a belt as at 3 and pulleys 4, to one or more shafts 5, which shafts are suitably connected so that power may be transmitted through the series. Each of these shafts is provided with cranks 6, and connecting rods 7 extend upwardly to cross-heads 8 which are slidable in guides 9. These guides are suitably braced or supported to prevent side oscillation. Secured to and extending above the guides are other guides 10 within which the rods 11 are slideable vertically. These rods carry at the upper end ribs 12 which are preferably made of aluminium, sufficiently stiff, and jointed or hinged to the rods 11, at the upper end, as shown at 13. The extension rods 14 connect the ribs with the slidable rings 15 which are fitted to the vertical rods 11. The ribs 12 are covered with any suitable strong flexible covering, such as silk, which may be cut to fit, and being secured to the ribs, the meeting edges may be attached to a separate or independent rib as at 16 by any suitable clamping devices. The operation of this portion of the device will be similar to the rapid opening and closing of an umbrella.

The mechanism hereinbefore described operates to reciprocate the rods 11 in their

guides, and when pushed upwardly the parachute-like structures will be wholly or partially closed and caused to move freely in that direction. As soon as the return stroke is made by means of the crank 6, the parachute will open by the pressure of the air, and will thus act with a pulling force, which is designed to raise the apparatus, or to so lighten, that by the assistance of a comparatively small gas-holder, the desired effect will be produced.

The proportion and size of the parts will be controlled by the number of parachute-like structures, the size and the rapidity of their reciprocations. These devices are intended solely to raise the apparatus to any desired height, and the apparatus may be balanced by varying the rapidity of reciprocation of the different parachutes so that if the tendency is to raise one side or end more than the other, the movement of the raising devices at that end or side may be made less rapid than those upon the other side. This can be effected by means of friction clutches connected with the propelling shafts, so that by a certain amount of slippage of the clutches, the rapidity of movement of the devices may be controlled.

In order to propel the apparatus in a direction in the line of travel, I have shown a propeller 17 carried upon a shaft 18, and power may be transmitted to rotate this shaft from bevel or other gearing, or well known propelling devices as at 19. A friction clutch 20 serves to connect and disconnect the line of shafting, and by means of this clutch, the movements of the propeller may be controlled, as previously described, for the elevating devices.

21 is a rudder conveniently located with relation to the propeller, and by means of tiller ropes, or other well known connections, the rudder may be turned to direct the course of the apparatus. It will be understood that the single propeller, and the single rudder represent any number of these devices which may be found desirable to employ, and various modifications may be made of the apparatus, following well known practice in such apparatus without departing from the principle of my invention. Rigidly mounted upon the rods 11 are stops 22 and 23 for the purpose of limiting the opening and closing movement of the parachutes.

Having thus described my invention, what I claim and desire to secure by Letters Patent is—

1. In an aerial machine, a frame with a plurality of spaced shafts journaled across it and having cranks at their outer ends, vertical standards fixed to the frame contiguous to the cranks, vertically slotted guides fixed to the standards, cross-heads slidable in the slots of the guides and connections between said rods and the cranks, guided rods connected with the cross-heads, said first-named guides having other guides at the upper ends through which said rods pass, and conical flexible ribbed and expansible structures carried on the upper ends of the rods and movable therewith.
2. In an apparatus of the character described, a frame, a series of flexible ribbed foldable cones, vertically guided and slidable rods upon the upper ends of which the cones are carried, transverse shafts with cranks at the ends outside of the ends of the frame, with which the cone-carrying rods are connected, shafts and gears by which the crank

shafts are caused to revolve in unison, and a motor from which power is transmitted to drive the gears.

3. In an apparatus of the character described, a plurality of flexible ribbed foldable cones, vertically guided and slidable rods upon the upper ends of which the cones are carried, a series of parallel transverse shafts having cranks at the outer ends with which the cone-carrying rods are connected, shafts and transmission gears connecting the crank shafts, a longitudinally journaled propeller bearing shaft, a motor and intermediate mechanism to transmit power to the crank and propeller shafts in unison, and clutches with actuating means whereby the propeller, or either end of any crank shaft, may be engaged or disengaged.

In testimony whereof I have hereunto set my hand in presence of two subscribing witnesses.

BARTHOLOMEW CONNOLLY.
